UNITED STATES PATENT OFFICE

2,097,549

CARPET SWEEPER DUMPING MECHANISM

Norman W. Cummins, Louisville, Ky., assignor
to Adler Manufacturing Co., Incorporated,
Louisville, Ky., a corporation of Kentucky

Application December 29, 1933, Serial No. 704,497

6 Claims. (Cl. 15—41)

This invention pertains to the structure of a dust pan dump lever mechanism forming a part of a portable carpet sweeper equipped with a rotary brush actuated from supporting wheels.

5 The subject matter of this application has a direct relation to that embraced in my United States Patent No. 1,993,296, granted March 5, 1935, for a "Sweeper".

The main object of this invention is to provide 10 a mechanism for opening and closing the dust pans by a force to be supplied by a human thumb and one finger, and without disturbing the equilibrium of the sweeper body when supported by the handle alone; also to minimize the force required to overcome a given spring pressure employed to maintain the pans closed during sweeping operations.

Another object is to provide means for retaining the dust pans in an open position while 20 discarding collected dirt particles without adding additional parts to accomplish the desideratum and independently of the force employed to effect the opening.

Still further objects or advantages, subsidiary 25 or incidental to the aforesaid objects, or resulting from the construction or operation of the invention as it may be carried into effect, will become apparent as the said invention is hereinafter disclosed.

30 *Drawing*

The invention is more particularly described and ascertained hereinafter, by way of example, having reference to the accompanying drawing wherein:

35 Figure 1 is an end view of a carpet sweeper housing with sections of the end cover and the end wall cut away, as well as the wheels and their axles removed to more clearly disclose the details of the dumping mechanism for the dust 40 collecting pans.

Fig. 2 is a bottom view of Fig. 1 substantially in its entirety, except that only a portion of the length of the sweeper is shown.

45 Fig. 3 is directed to a minor modification of the manually actuated rod to provide a means for locking the dust pans in an open position.

Fig. 4 is a modification of Fig. 1 to illustrate a 50 practicable rearrangement of the identical parts to provide means to yieldingly retain the pans in either the open or the closed position independently of the operating force.

Structure and operation

55 Numeral 10 indicates the end wall of the

sweeper housing, 11 a plate attached thereto and which is organized to support wheels, axles and their appurtenances which are not shown. Bearing 12 is a bushing fashioned with a shoulder and riveted on to the plate so as to become a permanent part thereof to support shaft 13, to one end of which is keyed lever or arm 14, while lever or arm 15 is keyed to the other end. It will be noted that the ends of the arms 14 and 15 adjacent shaft 13 have been formed with projecting areas which serve as collars for the shaft and abut the ends of the bearing 12 and thereby completely close same. This is obviously an enduring bearing of a very high order wherein the projecting areas of the arms prevent any egress of dust from the dust chamber even during rapid rotation of the brush when the air is highly agitated. To the lower end of lever 15, push bar 16 is pivotally connected by pivot 17 while the outer end of bar 16 is slidably supported by slot 18 formed in cover 19, which is removably attached to the end wall 10. Notch 16b of bar 16 in the modification shown in Figure 3 is so located that it can engage the margin of slot 18 and thereby lock all the moving parts of the dumping apparatus in the incident position, with the result that the pans will be held in the open position independently of the actuating force. A slight vertical pressure will release these parts to respond to the action of spring 21 to effect closing of the pans, which is dealt with herein-after.

Arm 14 is formed with a hook or projecting lug 20 which at all times carries the apex of inverted V shaped dump lever spring 21 while the ends 35 of said spring have a right angle bend to form arms 22, 23, each one being disposed into upturned edges of dump lever pans 24, 25. These in turn are carried on pivots or short shafts 26, 27 which are permanently attached to plate 11.

By lodging the ball of a human finger on the inner wall 19a of the cover and the thumb against the arm 16a of bar 16, and exerting a mild squeezing action, bar 16 travels in a path substantially parallel to the horizontal and moves lever 15 about its axis which in turn rotates shaft 13 sufficiently to thereby cause arm 14 to travel upward and pull spring 21 from its lower dotted rest position to the upper dotted position and thereby cause the dust pans 24, 25 to open and assume the position indicated by the dotted lines representing same in Fig. 1. Upon release of the pressure, the spring will return all the parts to their normal position.

In Fig. 4 the lug 20 is sufficiently closed to 55

retain the apex of spring 21 against force applied in either direction, which is employed to push or pull the ends of the spring over the center line described through the centers of pivots 26, 5 27, after which the spring toggles and forces the pans to the closed or open position. This structure differs from that disclosed in Fig. 1 by a minor rearrangement and relation of the travel of arm 14 and/or the length of spring 21.

10

Scope

The drawing employed to disclose this invention and the specification thereof, is in terms of my improvements as applied to the conventional 15 housing consisting of assembled pieces of wood. In the application of this invention to a unitary drawn sheet metal housing, the separate pieces would be eliminated, consequently the dust pan pivots would be mounted directly into the ends 20 of the integral housing and the dump lever bearing 12 fixed into one of the walls. Hence claims are directed to embrace either structure, as the teachings recorded herein are applicable to either type without the exercise of invention.

25 Other modifications, rearrangements and eliminations can be indulged without departing from the spirit of my invention, therefore I wish to be limited only by the following claims:

I claim:

- 30 1. A dumping mechanism attached to a vertically disposed end member of a carpet sweeper housing, comprising a shaft pivotally mounted in a bearing associated with said end member, an arm keyed to said shaft, said arm engaging the 35 central portion of a spring cooperating to open and close a pair of dust pans, and means employed to actuate said mechanism, including another arm keyed to said shaft, said arms circumferentially projecting beyond said bearing and 40 cooperating with the bearing to retain the shaft in a selected position and completely close the ends of said bearing.
2. A dumping mechanism attached to a vertically disposed end member of a carpet sweeper 45 housing, comprising a shaft pivotally mounted in a bushing associated with said end member, an arm keyed to the inside end of said shaft and circumferentially projecting beyond said bushing, said arm engaging the central portion of a 50 spring cooperating to open and close a pair of dust pans, and means employed to actuate said mechanism, including another arm keyed to said shaft, said inside arm cooperating with the shaft and bushing to effectively protect said bushing 55 against the egress of dust from said housing.
3. A dumping mechanism attached to a vertically disposed end member of a carpet sweeper housing, comprising a shaft pivotally mounted in a bearing and extending through said end

member, a short arm keyed to one end of said shaft, said arm engaging the central portion of a spring organized to open and close a pair of dust pans, means employed to actuate said mechanism, including a long arm keyed to said shaft, said arms circumferentially projecting beyond said bearing and cooperating with the bearing to retain the shaft in a selected position and completely close the ends of said bearing. 5

4. A dumping mechanism attached to a vertically disposed end member of a carpet sweeper 10 housing, a removable cover attached to and substantially covering the vertical end of said housing and surrounding a portion of said mechanism, said mechanism comprising a detachable 15 chassis plate, and a shaft pivotally mounted in a bushing lodged in said plate, an arm keyed to said shaft, said arm engaging the central portion of a spring cooperating to open and close a pair of dust pans, and means to transmit force to 20 actuate the said mechanism including another arm keyed to said shaft and connected to a bar extending through said cover.

5. A dumping mechanism attached to a vertically disposed end member of a carpet sweeper 25 housing, a removable cover attached to and substantially covering the vertical end of said housing and surrounding a portion of said mechanism, said mechanism comprising a detachable chassis 30 plate, and a shaft pivotally mounted in a bushing and extending through said plate and the end of said housing, a short arm keyed to one end of said shaft, said arm engaging the central portion of a spring cooperating to open and close a pair of dust pans, and means to transmit force to 35 actuate the said mechanism including a long arm keyed to said shaft and connected to a bar extending through and slidably in said cover.

6. A dumping mechanism attached to a vertically disposed end member of a carpet sweeper 40 housing, a removable cover attached to and substantially covering the vertical end of said housing and surrounding a portion of said mechanism, said mechanism comprising a shaft pivotally mounted in a bushing associated with said 45 end member, a short arm keyed to one end of said shaft, said arm engaging the central portion of a spring cooperating to open and close a pair of dust pans, and a long arm keyed to said shaft and pivotally connected to a notched bar slidably 50 extending through said cover and employed to actuate said mechanism, said bar being organized to lock said mechanism by engagement of said notch with said cover, said short arm circumferentially projecting beyond the bushing and 55 cooperating with the shaft and bushing to effectively protect said bushing against the egress of dust from said housing.

NORMAN W. CUMMINS.
